UNITED STATES PATENT OFFICE.

JAMES B. GILLHAM, OF MERRITT, ILLINOIS.

CAR-COUPING.

SPECIFICATION forming part of Letters Patent No. 248,159, dated October 11, 1881.

Application filed August 10, 1881. (Model.)

To all whom it may concern:

Be it known that I, JAMES B. GILLHAM, of Merritt, in the county of Scott and State of Illinois, have invented a new and Improved 55 Car-Coupler, of which the following is a specification.

This invention belongs to that class of devices that are self-couplers; and it consists of a draw-head having tongues projecting rearward into corresponding sockets or slots in the draw-bar and carrying springs on their ends, and provided, also, with a square collar fitting over the end of the draw-bar, said tongues having vertical perforations corresponding with 10 the openings in the draw-bar for the reception of the coupling-pin, which latter, when coupling, holds both draw-head and coupling-link in position; and it further consists of a peculiarly-shaped coupling-pin and novel devices 15 for uncoupling and holding the coupling-pin uncoupled, all of which will be hereinafter described.

In the accompanying drawings, Figure 1 is a partly-sectional side elevation of the device 25 applied to a car on line xx , Fig. 3, showing the manner in which a car is coupled. Fig. 2 is a partly-sectional side elevation of the same on line xx , Fig. 3, showing the manner in which a car is uncoupled. Fig. 3 is a vertical 30 sectional front elevation on line yy , Fig. 1.

Similar letters of reference indicate corresponding parts.

In the drawings, A represents a car.

B is the draw-bar attached thereto, having 35 three parallel slots or sockets, $a a b$, extending through its face rearward. The central socket, b , is of less depth than the others, and is designed to receive the coupling-link E. The sockets $a a$, one above and the other below the 40 socket b , are designed to receive the tongues $c c$ of the draw-head C. Through the draw-bar B is a vertical aperture, d , designed to receive the coupling-pin F.

The face C' of the draw-head C may be of 45 any desired shape, but preferably with a flaring mouth, as shown at f , for convenience of coupling high or low. In the back of the head of the draw-head C is a square groove, g , which forms a collar, h , all around the back of said head, and from the said head are two rearward-projecting tongues, $e e$, that are designed to enter the draw-bar sockets $a a$, so that when

said draw-head C is in place the collar h fits over the end of the draw-bar B, thereby preventing vertical or lateral movement of said 55 draw-head C. On the ends of said tongues e are fixed spiral springs $l l$, that bear against the bottoms of the sockets $a a$, and thereby serve to force said draw-head C outward, so as to force that portion of the upper tongue e 60 in rear of its aperture m , which portion may be called a "stop," n , against the coupling-pin F, to hold the latter up, as shown in Fig. 2, when the cars are uncoupled, and also to force both stops n against said pin F, to hold it 65 steady when the cars are coupled.

In order to hold the cars uncoupled, even when their draw-heads are in contact, and consequently forced rearward against their respective draw-bars, a rod, G, provided with 70 a handle, o , reaching above the top of the car A, and having a loop, p , about midway of its length, is connected with the head of the coupling-pin F, said rod G being supported in an upright position by a staple, s , in the front of 75 the car A. By pulling up said rod G, and engaging the loop p on a pin, r , in the front of the car A, the said pin F is held in the position shown in Fig. 2.

In coupling cars the coupling-link E from 80 an opposite car enters the socket b , and the draw-heads of the cars come in contact with each other with the effect of forcing the draw-head C into the position shown in Fig. 1, (C' representing the draw-head of an opposite car,) 85 whereby the tongues $e e$ are forced rearward, and the coupling-pin F thereby released to drop through the apertures $d m$ and link E. The pin F has a conical head, t , formed by reducing the said pin at t' , and the square shoulder of said head t , catching against the under side of the stop n of the upper tongue e , prevents the said pin F from being too far withdrawn. 90

About the top of the draw-bar B is secured 95 a frame, B' , to restrict the lateral swinging of the pin F when withdrawn from the said draw-bar B.

This coupling device can easily be applied to any car, and is simple, strong, and durable. 100

Having thus fully described my invention, I claim as new and desire to secure by Letters Patent—

1. In a car-coupler, the combination, with

the fixed draw-bar B, provided with slots *a a*, containing springs *l l*, apertures *d*, and the coupling-pin F, of the sliding draw-head C, provided with tongues *c c*, having apertures *m*, substantially as herein shown and described.

5 2. In a car-coupler, the combination, with the fixed draw-bar B, having slots *a a b* and apertures *d*, movable socketed draw-head C, provided with tongues *c c*, having apertures

m, and springs *l l*, of the pin F, reduced at *t'*, 10 and having conical point *t*, whereby the pin is prevented from being too far withdrawn and the draw-head C retained in position, substantially as herein shown and described.

JAMES BECRAFF GILLHAM.
